UNITED STATES PATENT OFFICE.

BERT ACKERMAN, OF CHESTER, VERMONT.

ROTARY RASP.

1,023,406.

Specification of Letters Patent. Patented Apr. 16, 1912.

Application filed December 7, 1911. Serial No. 664,360.

To all whom it may concern:

Be it known that I, BERT ACKERMAN, a citizen of the United States, residing at Chester, in the county of Windsor and State 5 of Vermont, have invented certain new and useful Improvements in Rotary Rasps; and I do declare the following to be a full, clear, and exact description of the invention, such as will enable others skilled in the art to 10 which it appertains to make and use the same.

This invention relates to improvements in rotary rasps.

One object of the invention is to provide a 15 rasp of this character having an improved construction and arrangement of operating mechanism whereby a rotary motion is imparted to the bit of the rasp.

Another object is to provide a rotary rasp 20 which will be simple, strong, durable and inexpensive in construction, efficient in operation and having means whereby the operating mechanism of the rasp may be adjusted and the wear thereof taken up.

25 With these and other objects in view, the invention consists of certain novel features of construction, and the combination and arrangement of parts as will be more fully described and claimed.

30 In the accompanying drawings; Figure 1 is a plan view of my improved rasp; Fig. 2 is a side view thereof; Fig. 3 is a horizontal section; Fig. 4 is a vertical cross section on the line 4—4 of Fig. 3.

35 My improved rasp comprises a handle 1 having formed on its outer end a hollow head 2 having a forked end, said fork comprising arms or members 3 and 4. The handle is of tubular construction or has formed 40 therethrough a longitudinal bore 5 the purpose of which will hereinafter appear.

45 Revolubly mounted in bearing apertures formed in the arms 3 and 4 of the forked end of the head is a rasp bit supporting and operating shaft 6, said shaft being enlarged and flattened for a portion of its length near one end and having on its reduced end a bevel gear pinion 7. On the shaft 6 is fixedly mounted the bit 8 of the rasp, said 50 bit being of cylindrical form and of any suitable size. The cylindrical surface of the bit is serrated or has thereon any suitable form of coarse or fine filing or rasping teeth.

55 The bore or passage through the bit with which the shaft 6 is engaged is flattened for a portion of its length to correspond with

the shape of the flattened portion of the shaft whereby the bit is held against rotation on the shaft.

The arm 3 of the forked outer end of the head 2 is hollow or has formed therethrough a bearing passage 9 and a recessed outer end 10. In the bearing passage 9 is revolubly mounted a drive shaft 11 having on its outer end a bevel gear pinion 12 which is disposed in the recess 10 and has an operative engagement with the bevel gear pinion 7 on the adjacent end of the rasp operating shaft. The inner end of the drive shaft 11 extends a suitable distance into the hollow head 2 70 and has fixed thereon a bevel gear pinion 13 which is operatively engaged with a similar pinion 14 on the shaft 15 of an electric motor 16 arranged in the hollow head 2 of the handle. To the motor 16 are connected the 75 inner ends of current conducting wires 17 which pass through the bore 5 of the handle and are connected to any source of electric supply whereby the motor is driven, and through the shaft 11 and gears thereon, 80 drives the rotary bit 8 of the rasp.

The end of the bit supporting shaft 6 in the fork arm or member 4 has therein a threaded socket 18 with which is engaged an adjusting screw 19 which engages a shaft 85 holding plate 20 pivotally connected at one end to the outer side of the arm 4 and adapted to be swung across the bearing opening in said arm whereby the outer end of the opening is covered, said plate having on its 90 inner end a notch 21 adapted to be engaged with a plate fastening screw or headed stud 22 arranged in the adjacent side of the arm 4 as shown. The plate 20 when in an operative position forms a stop with which the 95 adjusting screw 19 in this end of the bit supporting shaft 6 is engaged and by means of which the shaft is adjusted and the pinion 7 on the opposite end thereof held in operative engagement with the pinion 12 on 100 the outer end of the drive shaft. By providing the adjusting screw 19 it will be seen that any wear occurring in the pinions 7 and 12 may be readily taken up and a proper or operative engagement maintained between 105 these parts.

As hereinbefore stated the bit 8 of the rasp may be of any suitable size and the working surface thereof formed in any suitable manner for different kinds of work. 110 By supporting the bit in the manner described the same may be readily removed

and exchanged for a coarser or finer or different style of bit, thus permitting the same handle and operating mechanism to be used with a number of different style bits.

5 From the foregoing description taken in connection with the accompanying drawings, the construction and operation of the invention will be readily understood without requiring a more extended explanation.

10 Various changes in the form, proportion and the minor details of construction may be resorted to without departing from the principle or sacrificing any of the advantages of the invention as claimed.

15 Having thus described my invention, what I claim is:

A rotary rasp comprising a handle having on one end a head, bearing members arranged on said head, a bit supporting and 20 operating shaft revolvably mounted in said members, a bit fixed on said shaft, a drive

shaft revolvably mounted in said members, and having its outer end geared to the adjacent end of the bit supporting and operating shaft, means whereby said drive shaft 25 is driven, a stop plate pivotally secured to one of said bearing members and an adjusting screw arranged in the adjacent end of the bit supporting and operating shaft and adapted to engage said stop plate whereby 30 the bit supporting and operating shaft may be adjusted and held in its adjusted position to properly engage the geared end thereof with the gear on the adjacent end of the drive shaft.

35 In testimony whereof I have hereunto set my hand in presence of two subscribing witnesses.

BERT ACKERMAN.
